United States Patent Office

Des. 212,277
Patented Sept. 24, 1968

212,277

DECANTER

Walter T. Heintze, New Canaan, Conn., assignor to Schenley Industries, Inc., New York, N.Y., a corporation of Delaware

Filed Sept. 20, 1967, Ser. No. 8,674

Term of patent 14 years

(Cl. D9—137)

FIG. 4

I claim:

The ornamental design for a decanter, as shown.
